UNITED STATES PATENT OFFICE.

HENRY GRENON, OF NEW HAVEN, CONNECTICUT.

RAZOR-STROPPING DEVICE.

SPECIFICATION forming part of Letters Patent No. 554,867, dated February 18, 1896.

Application filed April 19, 1895. Serial No. 546,330. (No model.)

To all whom it may concern:

Be it known that I, HENRY GRENON, a citizen of the United States, and a resident of the city of New Haven, county of New Haven, 5 State of Connecticut, have invented a new and useful Improvement in Razor-Stropping Devices, which is fully set forth in the following specification, together with the drawings which form a part thereof, and in which like 10 letters of reference represent like parts in all the figures.

Figure 1 is a perspective view of the razor-stropping device with the razor attached; Fig. 2, a transverse section of the frame, showing 15 the carrier in elevation; Fig. 3, a longitudinal section through the frame and carrier; Fig. 4, an elevation of the razor-holder with one side of the blade-holder broken away; Fig. 5, a side elevation of one side of the carrier.

20 The object of this invention is to make a razor-stropping device for handling a razor while stropping the same and allowing the razor to automatically turn on its back when the motion of the handling device is reversed.

25 The rectangular frame A, made of steel or other suitable material, has a handle a at one end and a swivel loop or eye a' at its other end, fastened in any well-known manner. Mortises B and B' extending longitudinally 30 are formed on both sides of the frame at one end thereof. Rollers C and C' are affixed on the inside of the frame A and near the ends of and transversely with said frame, over which rollers extends the endless strop E. 35 The axle c' on which the roller C' rotates is journaled in the sides of the frame A near the swivel end thereof. The axle c on which the roller C rotates is journaled in the blocks D and D', which fit in the mortises B and B'

40 and have longitudinal play therein. Attached to blocks D and D' are screws extending longitudinally in said mortises and through the end of the frame A at the point d and d' and having screw-nuts d² and d³ for 45 the purpose of adjusting said blocks and rollers C attached thereto, so as to tighten or loosen the strop E as may become necessary. The axles c and c' extend beyond said frame and are held in position by screw-nuts c² and c³.

50 The travelers F and F' are constructed with a longitudinal recess f and a vertical recess

f', constructed with two flanges f² and f³, extending toward each other, forming the grooves f² and f³. The travelers F and F' are 55 thus adapted to fit over and embrace the sides of the frame A to move longitudinally on the frame A. The carrier G with an end g, to which is attached a handle g' and the sides g² and g³, said sides passing through the 60 recesses f' of the travelers F and F' and are embraced thereby, allowing the carrier G to be moved vertically in said travelers. A blade-holder H, having its two sides inclined 65 toward each other, is secured to a metal rod h passing through the sides of the carrier G. A cog-wheel I is attached near one end of the rod h within the carrier. The opposite end of said rod extends beyond the carrier a sufficient length to allow a spring-clamp i to be 70 attached to said rod for the purpose of holding the handle of the razor in place. A curved metal spring J in the blade-holder is attached thereto and secures the blade of the razor firmly in place in the blade-holder and adapts 75 it for using various sizes of razors.

A friction-roller K on an axle k journaled to the sides of the carrier G has connected rigidly therewith a gear-wheel k' which meshes with the wheel I. The gear-wheel k' is partially broken away at k² and k³, so that the lower face of the teeth at k² and k³ is adapted 80 to come in contact with the end of the carrier G and limit the rotation of the friction-roller K to the arc of the circle of the gear-wheel k'. A thumb-screw L, having a limited vertical play in the slot g⁴ in the side of the carrier G, is adapted to adjust the carrier so 85 that the roller K may be adjusted to properly rest on the strop. 90

The operation of the device is as follows: The razor-blade is inserted in the blade-holder, being held in place by the spring and the handle inserted in the spring-clamp. Upon the forward movement of the carrier 95 by means of the handle, which at the same time is drawn slightly downward, the friction-roller bearing against the lower part of the strop by the means of the gearing k' and I turns the blade-holder, bringing the razor-blade in contact with the strop. The gear-wheel k' broken away at k² and k³ and the thumb-screw L limit the pressure of the razor-blade upon the strop. Upon the reverse 100

movement of the carrier the friction-roller is rotated in the opposite direction, and by means of the gearing the blade-holder automatically reversed to bring the opposite side 5 of the razor-blade in contact with the strop.

Having now described my invention, what I claim is—

1. In a razor-stropping device, the combination of a frame, a strop in said frame, travelers connected to said frame and capable of longitudinal movement; a carrier mounted in said travelers and capable of vertical movement, a blade-holder attached to said carrier and mechanism for operating said blade-holder upon the longitudinal movement of said travelers, substantially as described.
2. In a razor-stropping device, the combination of a frame; a strop held in said frame; travelers connected to said frame and capable of longitudinal motion; a carrier embraced in said travelers and capable of vertical movement; a blade-holder attached to said carrier; a friction-roller affixed to said carrier and adapted to bear on said strop; and gearing connecting said friction-pulley with said blade-holder, substantially as described.

3. In a razor-stropping device, the combination with an endless strop, of a carrier, a blade-holder connected to said carrier, a friction-roller in said carrier and means for operating said blade-holder to bring the razor-blade held therein in contact with the upper strop when said roller is in contact with the under strop, substantially as described. 35

4. In a razor-stropping device, the combination of a frame; travelers connected to said frame and capable of longitudinal motion; a carrier embraced in said travelers and capable of vertical movement; a blade-holder and friction-roller mounted in said carrier; 40 and a gear-wheel connected with said friction-roller meshing with a gear-wheel connected to said blade-holder and having shoulders adapted to limit the rotary movement of said friction-roller, substantially as described. 45

In witness whereof I have hereunto set my hand this 16th day of April, 1895.

HENRY GRENON.
